US00D407657S

United States Patent [19]

Fushiya et al.

[11] Patent Number: Des. 407,657

[45] Date of Patent: **Apr. 6, 1999

[54] **CONVERTER FOR AN ELECTROMAGNETIC FLOW METER**

891638 3/1994 Japan .
939892 11/1995 Japan .

[75] Inventors: **Nobuhiro Fushiya, Yokohama; Takashi Kohara, Tachikawa, both of Japan**

[73] Assignee: **Kabushiki Kaisha Toshiba, Kawasaki, Japan**

[**] Term: **14 Years**

[21] Appl. No.: **78,224**

[22] Filed: **Oct. 24, 1997**

[30] **Foreign Application Priority Data**

Apr. 25, 1997 [JP] Japan 9-52799

[51] **LOC (6) Cl. 10-04**

[52] **U.S. Cl. D10/96**

[58] **Field of Search D10/96; 73/861.11-861.18**
